RUBBER ROLLING HOOP FOR STEEL
BARRELS

William I. Hanrahan, New York, N. Y., assignor
to The Petroleum Iron Works Company of
Ohio, Sharon, Pa., a corporation of Ohio

Application September 7, 1938, Serial No. 228,835.

2 Claims. (Cl. 220—71)

The invention relates to sheet metal barrels or drums and provides certain improvements in the rolling provisions therefor.

It is conventional practice to provide metal containers of the type indicated with rolling hoops sometimes manifested as outwardly directed circumferential corrugations of the shell and sometimes as rails or bars of I-beam or other section shrunk on or otherwise secured to the shell. Metal hoops are objectionable because they operate to cut and otherwise damage polished and other expensive floors and because they operate to mar the surfaces of adjacent barrels and drums. It has heretofore been proposed to replace the metal hoops with rubber and other elastic hoops but they have not been satisfactory for one reason or another and because no satisfactory means were suggested for anchoring them.

According to my invention the shell of the container is provided with relatively closely spaced circumferential beads for the purpose and with the result of anchoring a generally dome-shaped rubber structure having grooves to accommodate the beads and flanges or shoulders extending beyond the beads and secured by contracting bands, the dome-shaped structure being of sufficient depth or thickness to constitute a rolling hoop. The invention in its preferred form is illustrated in the accompanying drawing, forming a part hereof, wherein—

Figure 1 is a sectional view of a sheet metal barrel or drum having a rubber hoop constructed, anchored, and secured in accordance with my invention.

Fig. 2 is a view principally in side elevation showing the means for contracting the bands.

In the drawing, 5 represents the shell of a conventional sheet metal barrel or drum, headed as usual. 6 denotes circumferential beads formed as outwardly directed corrugations of the shell and relatively closely spaced by seating surface 7.

The paired beads serve to anchor a rubber hoop 8 which in section is of general dome-shape. The hoop is by preference of solid construction with shoulders or flanges 9 having overlying grooves or channels to accommodate contractible bands 10. Inwardly of the shoulders and relatively spaced apart are grooves 11 contoured to fit the beads. The hoop may be applied as an endless band or it may be of the split type with the ends joined as by cementing, vulcanization or in any other conventional way. When the parts are assembled and arranged in the manner stated, the bands 10 are joined and contracted through the medium of turnbuckles 12.

It will be manifest that by the construction and arrangement stated and by virtue of the relative angular arrangement of the anchoring beads and the securing bands, the hoop will be properly anchored and comparatively free of tendency toward lateral deformation.

Having described the invention, what is claimed as new is:

1. A metal barrel or drum whereof the cylindrical wall is provided with a channular seat having a flat bottom and sloping side walls defined by a pair of circumferential arcuate beads, combined with a solid rubber hoop whereof the main body portion has a rounded tread and a bottom rib to fit the channular seat, said rib being defined by a pair of grooves which match the beads and snugly fit the same, said main body portion having flexible flanges extending beyond the beads, and means overlying the flanges to contract them and thereby hold the hoop rigidly stationary with relation to its seat.

2. The invention set forth in claim 1 in which said overlying means comprises a wire with threaded ends and a small turnbuckle engaging said ends, the wire and turnbuckle being well within the confines of the hoop.

WILLIAM I. HANRAHAN.
